DEHYDRATING METHOD AND APPARATUS

Walter A. Patrick, Jr., and John D. Elder, Baltimore, Md.; said Elder assignor to Crown Cork & Seal Company, Inc., Baltimore, Md., a corporation of New York

Application May 20, 1943, Serial No. 487,780

11 Claims. (Cl. 159—3)

This invention relates to method and apparatus for the dehydration or concentration of liquid material to a point where the material is still fluid. Fluidity of the material is required inasmuch as the invention contemplates treatment of the material while in flow. This requirement is outside of the circumstance that the solid state, as caused by freezing, is in any event avoided as detrimental to a rapid dehydrating action.

In processes heretofore proposed, the material has been frozen and maintained so while being sublimed. This procedure is slow and expensive by reason of the low temperature and the high vacuum necessary to be maintained. Whether physical or chemical desiccants are used for the sorption of the evolved vapors the desiccant, in use, undergoes a temperature rise, unless controlled, whereby its efficiency is impaired. It is the purpose of the present invention to automatically maintain the material against freezing, for rapid evaporation, and the desiccant against harmful temperature increase, by flowing the material from a zone of forced evaporation through the desiccant in heat exchanging relation therewith.

In some cases, as in the manufacture of adhesive from blood, it is only necessary to reduce the water content by a relatively small fraction of the original, and in such cases operation under the present invention enables the final product to be quickly reached. In case a substantially dry product is required, the present invention may be applied as a rapid first stage, and the product, still in liquid state, may be subjected to a second stage, for example utilizing apparatus such as is disclosed in our copending application Serial No. 478,734, filed March 10, 1943.

Apparatus in accordance with the invention is shown by way of example in the accompanying drawing, to which reference will now be made.

Reference numeral 1 designates as a whole an upright container comprising a main portion 2, a reduced sump portion 3, and a top 4. At its lower end, portion 2 is provided with a perforate floor 5 which supports a charge of balls, or the like, 6 of stable material.

From the top 4 a conduit 7 leads to the top 8 of a container 9 for any suitable sorptive material, physical or chemical, but preferably the former, for example silica gel. A partition 10 in the conduit 7 has an opening which can be closed by a valve gate 11.

The sump 3 is tapered downwardly to a bottom opening into which is connected a pipe 12 with

an interposed valve 13, and connected laterally into the bottom of the sump is a pipe 14 which is led through the bottom of container 9, then zig-zagged through the interior of the container 5 to provide a coil having vertical portions, and then is extended to terminate in a spray head 15 under the top 4 of the tank 1. A valve 16 is interposed in conduit 14 adjacent the sump and beyond the valve a pump 17, of any suitable type, 10 is interposed in the conduit. Fixed to the vertical portions of the coil in container 9 are a multiplicity of heat conducting fins 18 which are in good conductive contact with the conduit, which is itself of good heat conducting capacity, 15 and the spaces between the fins are packed with the desiccant. Between the legs of the coil perforate cylinders 19, for example made of wire mesh, are set in the container so as to define paths of flow vertically through the desiccant 20 which is packed about the cylinders. The pipe 14 is led through an opening in the partition 10, in which it is sealed, and has interposed therein a valve 20 just in advance of a T 21 from which the head 15 depends.

25 Connected into the bottom of the receptacle 9 is a conduit 22 which leads to a source of vacuum, not shown. It may be mentioned that a source of particularly high vacuum is not required and a steam jet evacuator of small capacity will ordinarily be adequate. Conduit 22 is equipped with a valve 23. Also leading into the bottom of container 9 is a conduit 24 for the introduction of hot air for the activation of the desiccant and this conduit is provided with a valve 25. An outlet conduit 26 for the activating fluid leads from the top of the container 9 and is provided with a valve 27.

30 A conduit 1' leads from the top of the container 1 to the top of a desiccant container 9', the conduit 1' having therein a partition 10' with an opening controlled by a valve gate 11'. A conduit 14' extends from the bottom of the sump to and through the container 9', through the partition 10', and to the opposite side of the T 21 35 from the conduit 14. Interposed in conduit 14' are the valves 16' and 20' and the pump 17'. Within the container 9' the conduit 14' is arranged and equipped in the same manner as above described with reference to the container 9. The container 9' is connectible with the vacuum source through a pipe 22' and a valve 23', and also associated with the container are the activating air ducts 24' and 26' equipped, respectively, with valves 25' and 27'.

40 45 50 55 The two desiccant chambers are provided so

that one may be used in the dehydrating operation while the desiccant in the other is being regenerated. In the drawing it is assumed that chamber 8 is to be used in the dehydrating process, and this being the case, valves 11, 16, 20, and 23 are open, whereas valves 13, 25, and 28 are closed. Valves 11', 16', 20', and 23' are closed, and valves 25' and 27' are opened. Consequently, with the suction device in operation, the pressure is lowered throughout the system up to the 10 valve gate 11' which isolates the container 9'. It is assumed that hot air is being supplied to the latter through conduit 24'.

With the system thus set, and preferably prior to the application of vacuum, the liquid to be dehydrated is introduced in predetermined quantity into the container portion 2 through the top opening 30 upon swinging open the cover 31. When the container has been charged the cover is closed and fastened so as to seal the opening 30. Upon starting pump 17, the liquid material is withdrawn from the bottom of the sump 3, passed through the coil in chamber 8 and then delivered by the head 15 as a spray on the bodies 6 over which the material flows by gravity substantially in film form so that very large surfaces are provided as an aid to evaporation. The evolved vapors are pulled downwardly through the body of desiccant and are adsorbed thereby. By reason of the evaporation occurring in the container 1 the temperature of the material tends to drop, and freezing might eventually occur unless counteracted. On the other hand, by reason of the condensation of the vapor by the desiccant, the temperature of the desiccant tends to rise. However, the heat of the desiccant flows into the material in the coil with the result that the temperature of the material is maintained above freezing while the desiccant is maintained at a substantially constant low and efficient operating temperature. The capacity of the desiccant for the purpose of maintaining the material being dehydrated at an above freezing temperature is determined by several factors; for example, when silica gel is used, the factors include the area of gel surface exposed to the heat conducting surfaces (i. e., to the coil and the fins 18), the thickness of the gel layers, and the temperature gradient between the gel and the material being dehydrated. This capacity is so related to the evaporation factors that the material will be maintained at an above freezing temperature and the desiccant will be maintained at an effective operating temperature.

A predetermined quantity of the liquid material having been introduced into the system at the start of the operation, the liquid level in the container 1 will fall to a certain level in the container when the calculated degree of concentration has been attained as the result of the continued circulation of the material through the system. In the drawing it is assumed that at this point the liquid will be at the level x in the sump 3, the level being observable by means of a gauge 32 associated with the sump. This level having been reached, valve 23 is closed, the pump is stopped, and valve 13 is opened so as to drain the dehydrated product from the container. In order to relieve the vacuum condition in the system, valve 27 may, if desired, be opened after valve 23 is closed. The material in pipe 14 between pump 17 and sump 3 will drain back into the latter. When the sump is empty, pump 17 is started and will act to withdraw any further material remaining in pipe 14 to the rear of the 75

pump and to propel the material in advance of the pump to the head 15 so as to clear the pipe 14 throughout.

If the desiccant in chamber 8 is still usable without regeneration, the above-described cycle may be immediately repeated. However, if the desiccant in chamber 8 requires regeneration, the dehydrating operation will be switched to the chamber 8', but before this operation is commenced it will ordinarily be necessary or desirable to flush out the system including the conduit 14. For this purpose, container 1 is charged with a flushing liquid which is circulated for some time by pump 17. Valve 13 is then opened and conduit 14 is cleared through the further operation of the pump. When the system has drained, valve 13 is closed, as are also valves 11, 16, and 20. Valves 25 and 27 are opened and the activating agent is applied.

The container 1 having been recharged with material to be dehydrated, valves 11', 16', 20', and 23' are opened, and valves 25' and 27' are closed. Upon setting pump 17' in operation, the dehydrating operation proceeds exactly as before except that the desiccant in chamber 8' is now functioning.

Where the material to be dehydrated has a substantial gaseous content, as in the case of blood, a preliminary degassifying step is desirably used in order to prevent undue foaming during dehydration. Degassification can be very effectively carried out by first freezing the material and then subjecting it to vacuum. The degassified material can then be thawed and introduced into the container 1. Or the frozen material can be broken up and introduced into the container in this form. In the latter case, in order to accelerate thawing, heat can be supplied by causing a flow of hot air through the top of container 1, for example by opening valves 25 and 27' while valve 27 remains closed. While we emphasize the carrying out of the dehydrating operation with the material in liquid form, this, of course, does not preclude the described preliminary freezing for the purpose of facilitating a degassifying operation.

It will be understood that the disclosed apparatus is merely representative and that variations therein and in procedural matters are possible under the invention and contemplated in the claims which follow.

We claim:

1. In the dehydration of a liquid material by the subjection of the same to forced evaporation and by the sorption of the evolved vapors in a desiccant, the method of heating the material and cooling the desiccant which comprises flowing a stream of the material being dehydrated in heat exchanging relation with the desiccant.
2. In the dehydration of a liquid material by the subjection of the same to forced evaporation and by the sorption of the evolved vapors in a desiccant, the method of heating the material and cooling the desiccant which comprises circulating the material through a zone wherein it is subjected to the forced evaporation and through the desiccant in heat exchanging relation therewith.
3. Apparatus for dehydrating a liquid material comprising a container for the material, a body of desiccant, a vapor suction line in connection with said container and in communication with said body of desiccant, and a conduit in connection with said container and passing through said body of desiccant and serving to conduct the

material in heat exchanging relation with the latter.

4. Apparatus for dehydrating a liquid material comprising a container for the material, a body of desiccant, a vapor suction line in connection with said container and in communication with said body of desiccant, and a circulatory system for the material including said container and including a portion passing through said body of desiccant whereby to provide for heat exchange between the latter and the material in said portion.

5. Apparatus for dehydrating a liquid material, comprising a container for the material, a conduit arranged to withdraw material from the container and to return the material thereto, a pump for moving the material through said conduit, a body of desiccant through which the conduit passes so that material in the conduit is brought into heat exchanging relation with said body, and a vapor suction line in connection with said chamber and in communication with said body.

6. Apparatus according to claim 5 wherein means is provided for delivering the material from the conduit to the container as a spray.

7. Apparatus according to claim 5 wherein the container contains a multiplicity of bodies onto which the material is delivered by said conduit for flow thereover substantially in film form.

8. Apparatus according to claim 5 wherein means is provided for delivering the material from the conduit to the container as a spray, and wherein the container contains a multiplicity of bodies which receive the material for flow thereover substantially in film form.

9. Apparatus for dehydrating a liquid material, comprising a container for the material, a conduit extending from the bottom of said container to a delivery point above the container, a pump interposed in said conduit operative to move the material through the circuit constituted by said container and conduit, a body of desiccant through which the conduit passes so that ma-

terial in the conduit is brought into heat exchanging relation with said body, and a vapor suction line in connection with said container and including said body.

5 10. Dehydrating apparatus for liquid material comprising a container for the material, a pair of desiccant containers, valved vapor conduits connecting the material container with the desiccant chambers respectively, valved suction conduits in connection with the desiccant containers respectively, valved inlet and outlet conduits for an activating fluid in connection with each desiccant chamber, whereby suction may be applied to the material container through either desiccant chamber while the desiccant in the other is being activated, and means for effecting heat exchange between the material and the desiccant in the chamber through which suction is being applied.

10 11. Dehydrating apparatus for liquid material comprising a container for the material, a pair of desiccant containers, valved vapor conduits connecting the material container with the desiccant chambers respectively, valved suction conduits in connection with the desiccant containers respectively, valved inlet and outlet conduits for an activating fluid in connection with each desiccant chamber, whereby suction may be applied to the material container through either desiccant chamber while the desiccant in the other is being activated, a circulatory system including the material container and one of the desiccant containers, a circulatory system including the material container and the other of the desiccant containers, and means for rendering 30 35 said systems selectively operative so that only the system including the desiccant chamber through which suction is being applied will be operative whereby heat exchange will be effected between the material and the desiccant in the 40 last mentioned container.
